UNITED STATES PATENT OFFICE.

EUGENE T. TURNER, OF ROCK ISLAND, ILLINOIS, ASSIGNOR TO ARTISTA PIANO
PLAYER COMPANY, OF MILAN, ILLINOIS, A CORPORATION OF ILLINOIS.

FALL-BOARD FOR PIANOS AND THE LIKE.

998,135.

Specification of Letters Patent. Patented July 18, 1911.

Application filed April 23, 1908. Serial No. 428,780.

To all whom it may concern:

Be it known that I, EUGENE T. TURNER, a citizen of the United States, residing at Rock Island, in the county of Rock Island 5 and State of Illinois, have invented certain new and useful Improvements in Fall-Boards for Pianos and the Like, of which the following is a specification.

This invention relates to improvements in 10 fall boards for pianos and the like more particularly adapted for use in pianos having pneumatic playing attachments, and the primary object of the invention is to provide an improved, simple and efficient device of 15 this character which is adapted to fold compactly in a very small space and one which will not project into the casing to interfere with the pneumatic actions.

A further object is to provide an im- 20 proved device of this character which may be readily removed to permit access to the pneumatic actions.

To the attainment of these ends and the accomplishment of other new and useful ob- 25 jects, as will appear, the invention consists in the features of novelty in the construction, combination and arrangement of the several parts hereinafter more fully de- 30 scribed and claimed and shown in the ac- companying drawing, illustrating an em- bodiment of the invention, and in which—

Figure 1 is a detail sectional view showing a portion of a piano casing with an improved fall board attached thereto con- 35 structed in accordance with the principles of this invention. Fig. 2 is a detail per- spective view of a portion of the fall board. Fig. 3 is a sectional view on line 3—3 of Fig. 1. Fig. 4 is a sectional view on line 40 4—4 of Fig. 3.

Referring more particularly to the drawing and in the present exemplification of the invention, the numeral 10 designates a portion of the casing of the musical in- 45 strument, 11 the keys, 12 a portion of the panel above the keys, and 13 is a portion of the pneumatic action.

The shelf 14 is supported adjacent the lower end of the panel 12 and projects for 50 any desired distance beyond the front there- of. Depending from the forward end of the shelf is an upright member 15, which is pivotally supported by its upper end as at 55 16 adjacent the shelf 14 and this upright member 15 terminates above the keys 11.

Secured to the lower face of the shelf 14 are any suitable number of yielding mem- 60 bers 17 preferably in the form of springs, the free extremities 18^a of which are adapted to engage the rear face of the upright mem- 65 ber 15, preferably adjacent the free end thereof and tend to hold the upright member in an inclined position by forcing the free end thereof forwardly.

A fall board 18 is pivotally supported as 70 at 19 (see Fig. 3) to a fixed portion of the casing 10 in such a position that the rear edge 20 thereof will stand adjacent the lower end of the upright member 15 and this mem- 75 ber 15 is provided with a forwardly pro- jecting portion 21 which is adapted to pro- ject over or beyond the edge 20 of the fall board 18 when the latter is lowered to form a dust proof joint between the upright 80 15 and the fall board 18 and the parts are held 75 in this position by means of the yielding members or springs 17 when the board 18 is lowered. Obviously the portion 21 does not project over the edge 20 of the fall board a sufficient distance to cause the parts 85 to be locked or jammed, but only to such an extent as to permit free movement of the parts.

Suitable supports 22 may be provided 85 which are adapted to rest upon a fixed por- 90 tion 23 of the casing for holding the free end of the board 18, and a member 24 is piv- 95 otally supported as at 25 to the free end of the fall board and is adapted to close the space between the fall board and the keys 90 when the fall board is lowered to the posi- 100 tion as shown in Fig. 1.

Projecting beyond the rear edge 20 of the fall board 18 are spaced arms or pro- 105 jections 26, which may be of any desired length and these arms project into the cas- 110 ing beyond the upright member 15. The casing of the instrument is provided with slots or openings 27 which may be formed in any desired or suitable manner and to the walls of these slots or openings may be se- 100 cured a suitable fabric, such as felt or the like.

When the fall board is raised from the po- 105 sition shown in full lines in Fig. 1 of the drawings, the upright member 15 will be moved about its point of pivotal support 16 and against the tension of the yielding members 17 by the rising movement of the fall board, which will cause the latter to 110

engage the forward edge of the projecting portion 21 and move the member 15 to the position shown in dotted lines in Fig. 1. As the fall board is raised the spaced arms 5 26 will enter the slots or openings 27 and will frictionally engage the walls thereof to hold the fall board in its raised position. When the fall board is lowered the friction 10 of the arms 26 against the walls of the openings will be overcome and the yielding members 17 will force the upright member 15 into the position shown in full lines in Fig. 1.

With this improved construction, it will 15 be apparent that the board may be folded in a very compact space and that it will not project into the casing to interfere with the pneumatic actions, thereby providing the necessary space for the actions without increasing the width of the piano casing.

In order that the invention might be fully understood the details of the foregoing embodiment have been thus specifically described, but

25 What I claim as new is—

1. In a musical instrument, the combination of a shelf, a pivoted upright member, a fall board pivoted to a fixed part of the casing, a portion of said member projecting over the adjacent edge of the board, and means for holding the upright member in a position to project over the said board when the latter is closed, said upright member being adapted to be moved about 30 its pivot by the rising movement of the board.

2. In a musical instrument, the combination of a shelf, a pivoted upright member, a fall board pivoted to a fixed part of the 40 casing, a portion of said member projecting over the adjacent edge of the board when the latter is lowered, and yielding means tending normally to hold the parts in such position, said member being adapted to be moved about its pivot by the board as the latter is raised and against the tension of the said yielding means.

3. In a musical instrument, the combination of a shelf, a pivoted upright member, 50 a fall board pivoted to a fixed part of the casing, a portion of said member projecting over the adjacent edge of the board when the latter is lowered, yielding means tending normally to hold the parts in such position, said member being adapted to be moved about its pivot by the board as the latter is raised and against the tension of 55 the said yielding means.

the said yielding means, and separate means for holding the board in a raised position.

4. In a musical instrument, the combination of a shelf, a pivoted upright member, a fall board pivoted to a fixed part of the casing, a portion of said member projecting over the adjacent edge of the board when 60 the latter is lowered, yielding means tending normally to hold the parts in such position, said member being adapted to be moved about its pivot by the board as the latter is raised and against the tension of 65 the said yielding means, and friction means for holding the board in a raised position.

5. In a musical instrument, the combination of a shelf, a pivoted upright member, a fall board adjacent the free end of the upright member, said board being pivoted to a fixed part of the casing, said upright member being provided with a portion projecting over the adjacent edge of the board when the latter is lowered, yielding means 70 for holding the member in such position, said member being adapted to be moved about its pivot by the board as the latter is raised, and means supported by the board and adapted to frictionally engage the casing to hold the board raised and against 75 the tension of the said yielding means.

6. In a musical instrument, the combination of a shelf, a pivoted upright member, a fall board adjacent the free end of the upright member, said board being pivoted to a fixed part of the casing, said upright member being provided with a portion projecting over the adjacent edge of the board when the latter is lowered, yielding means 80 for holding the member in such position, said member being adapted to be moved about its pivot by the board as the latter is raised, and an arm projecting from the board and beyond the edge thereof, the casing being provided with an opening and said arm being adapted to enter the opening and frictionally engage the wall thereof to hold the board in a raised position and against the tension of the said yielding 85 means.

In testimony whereof I have signed my name to this specification, in the presence of two subscribing witnesses, on this 10th day of April A. D. 1908.

EUGENE T. TURNER.
